Taubman & Taubman,

ATTORNEYS

UNITED STATES PATENT OFFICE.

PHILIP A. MYERS, OF ASHLAND, OHIO, ASSIGNOR TO F. E. MYERS & BROTHER, A CO-PARTNERSHIP CONSISTING OF FRANCIS E. MYERS AND PHILIP A. MYERS, BOTH OF ASHLAND, OHIO.

POWER-HEAD.

1,393,306.

Specification of Letters Patent. Patented Oct. 11, 1921.

Application filed August 30, 1920. Serial No. 407,025.

To all whom it may concern:

Be it known that I, PHILIP A. MYERS, a citizen of the United States, residing at Ashland, in the county of Ashland and State of Ohio, have invented certain new and useful Improvements in Power-Heads, of which the following is a specification, reference being had therein to the accompanying drawing.

10 This invention relates to an improved power head of the type shown and described in my copending applications, Ser. No. 351,966, filed Jany. 16th, 1920, and Ser. No. 351,967, also filed Jany. 16th, 1920, and 15 the present improvements relate to a type of oiling mechanism used in conjunction with such power head.

20 The object of my invention is the provision of a casing adapted to contain a quantity of lubricant, rotatable operating mechanism mounted within the casing, as also a substantially vertical guide within it and a slide mounted on the guide on which it reciprocates, and having means for connecting it with the apparatus to be operated by the power head, and a connection between such slide and the actuating mechanism, all of these devices being within the casing and adapted to be lubricated by the contained 25 lubricant, save the connection between the slide and the outside apparatus, which is without the casing.

30 Another object of my present improvement in reference to oiling devices is that as the reciprocating sleeve or member travels back and forth it shall cause a connected oiler in the form of a tube and valve to receive the lubricant generally contained in the power head casing and deliver it at or 35 near the other extremity of the sliding member, so as to reciprocate its bearing surface.

40 In the accompanying drawings:—

45 Figure 1 is a vertical, sectional view of the class of power head referred to above, with my improved oiler applied thereto; and

50 Fig. 2 is a transverse vertical, sectional view through the casing, sliding member and oiler, more clearly showing the construction.

55 The power head illustrated comprises a casing 1 adapted to contain a quantity of lubricant, the casing in this instance having a well 1^a divided off from the interior of the casing and adapted to receive not

only the lubricant but the oiler to be presently described. This casing has a removable cover 2 and a slotted opening 3 and has mounted within it a driving shaft 4 carrying pinions 5, as also a pair of driven gears 6, the latter having a wrist pin 7 operating a pitman 8 which occupies a position between the gear wheel 6. The pitman is connected at its upper end to a sleeve or sliding member 9 fitted to travel upon a guide or shaft 10. The upper end of the sleeve is fashioned to constitute a cup 11 to receive a lubricant in the manner presently to appear.

60 An oiling device is connected with the sleeve consisting of a tube 12 whose upper end, as shown at 13, is arranged to discharge into the cup 11 and whose lower end carries a valve casing 14 with a ball or other suitable valve 15 resting on a seat 16, the valve casing and its ball being adapted to enter the oil sump 2 when the sleeve moves in its lower field of travel. The ball is lifted by the resistance of the oil which flows past the ball into the tube 12. When 65 the tube is lifted, as on the up-stroke, the ball or valve seats and retains the oil so delivered into the tube. After a few strokes the tube will become filled with oil so that each additional stroke will cause an overflow of oil from the tube into the cup 11. As the sleeve reciprocates the lubricant will 70 be applied to the guide shaft and will work its way down between the sleeve and the shaft and meet whatever oil has entered at the lower end of the sleeve and between it and the shaft. In this way the sleeve is kept perfectly lubricated, without adjustment or manual manipulation, while the 75 general power mechanism within the casing is also perfectly and completely lubricated. The splashings are sufficient to keep the connection between the sleeve and the upper end of the pitman duly oiled.

80 In practice this is a very efficient and satisfactory oiler, perfectly lubricating the parts with economy of oil.

85 In practice also this power head mechanism has proved in large commercial use to be durable, highly efficient and smooth-working, and to transmit the rotary motion of the gear wheels to the reciprocating slide or member 9 in an effectual manner to enable the slide to perform the heavy duty of raising and lowering, smoothly and with- 90 95 100 105 110

out jar, long heavy pump piston rods with their pistons and loads of water, as well on the up as on the down stroke.

Having thus fully described my invention, what I claim as new and desire to secure by Letters Patent, is:—

1. In a power head, the combination, with a casing adapted to contain a quantity of lubricant, rotatable operating mechanism 10 therein, and a vertical guide within the casing, of a slide mounted on said guide, adapted to reciprocate and having means for connection with an apparatus to be operated thereby, and an operating connection between 15 said slide and the rotatable actuating mechanism within the casing.
2. In a power head, the combination, with a casing adapted to contain a quantity of lubricant, rotatable operating mechanism 20 therein, and a vertical guide within the casing, of a slide mounted on said guide, adapted to reciprocate and having means for connection with an apparatus to be operated thereby, an operating connection between 25 said slide and the rotatable actuating mechanism within the casing, and an oil pumping tube connected with said slide and adapted to deliver oil from the casing to the upper end of the slide.
3. In a power head, the combination, with a casing, rotatable operating mechanism 30 therein, and a vertical guide shaft in the casing and extending above the lubricant-

line, of a sleeve mounted on said shaft and adapted to reciprocate, an operating connection between said sleeve and the rotatable actuating mechanism, an oiler connected to the sleeve, adapted at one end to gather lubricant and at the other end to deliver the lubricant at the upper end of the sleeve. 35

4. In a power head, the combination, with a gear casing, rotatable operating mechanism therein, a vertical guide shaft in the casing and extending above the lubricant-line, and an oil well in the casing, of a sleeve 45 mounted on said shaft and having a cup in its upper end, an oiler comprising a tube connected to the sleeve, adapted at its lower end to enter said well and having a valve and adapted at its other end to discharge 50 oil into said cup.

5. In a power head, the combination, with a casing adapted to contain a lubricant, a well at the bottom of said casing divided off therefrom, a fixed guide shaft held by the 55 casing and extending above the lubricant-line, a sleeve mounted on said shaft and having a cup at its upper end, an oiler tube secured to said sleeve, adapted at its lower end to enter said oil well and having a valve in 60 said end and adapted at its upper end to discharge lubricant to said cup.

In testimony whereof, I affix my signature.

PHILIP A. MYERS.

DISCLAIMER.

1,393,306.—*Philip A. Myers*, Ashland, Ohio. POWER HEAD. Patent dated October 11, 1921. Disclaimer filed October 12, 1928, by the assignee by mesne assignments, *The F. E. Myers & Bro. Company*, the patentee, *Philip A. Myers*, concurring.

Hereby enters a disclaimer limiting claim 1 of said patent as follows:

By restricting the element "vertical guide" of said claim 1 to a single guide;

By restricting the element "slide mounted on said guide" to a single slide;

By restricting the element "means" for connecting said slide to the apparatus to be operated, to an arm on one side of the slide; and

By restricting the element "operating connection" between the slide and the actuating mechanism, to a pitman.

[Official Gazette October 30, 1928.]
